UNITED STATES PATENT OFFICE.

LESTER STEWART BARR, OF WASHINGTON, DISTRICT OF COLUMBIA.

TYPEWRITING MACHINE.

Application filed February 28, 1922. Serial No. 539,885.

To all whom it may concern:

Be it known that I, LESTER STEWART BARR, a citizen of the United States, residing at Washington, District of Columbia, have invented certain new and useful Improvements in Typewriting Machines, of which the following is a specification.

This invention relates to typewriting machines and more particularly to a check 10 tecting device for typewriters.

The object of the invention is to provide, in any standard make of typewriter, a separate type bar and key lever for making a series of non-inked indentations upon more or 15 less of the writing on a sheet for the purpose of preventing alterations therein.

To this end, the invention comprises a type bar having means for indenting a paper, such as a check, and constantly effective 20 means for operating the type bar and actuating the letter-feed ratchet mechanism without actuating the ribbon vibrator. By providing a separate key lever for this purpose, which will automatically cut out the 25 ribbon vibrator while actuating the letter-feed ratchet, the operator of a machine in which the invention is applied merely has to manipulate a particular key lever in order to produce the required indentations. Some 30

machines are already equipped with a ribbon cut out for the purpose of rendering the ribbon vibrator inoperative when making stencils, and with such machines it is possible to produce non-inked indentations 35 on a bank check, but with such machines the operator would have to manipulate the ribbon cut out prior to operating the particular key lever used; and this would require the operator's attention as well as time. With

40 a machine having my invention applied thereto, on the other hand, the operator merely has to manipulate a particular key lever without having his attention distracted and time consumed by the necessity of performing an antecedent operation.

Referring to the accompanying drawings for a specific disclosure of one embodiment of my invention:

Figure 1 is a vertical sectional view of a 50 typewriting machine having my invention applied thereto, and

Figure 2 is a detail view showing a face view of the type block employed for making the indentations.

55 Numeral 1 on the drawing designates the base of the typewriter. Corner posts 2 rise

from the base and a top plate 3 surmounts the posts and has mounted thereon the platen 4, ribbon holder 5 and other parts, not shown, of the typewriter mechanism. 60

The letter-feed ratchet mechanism comprises a ratchet bar 6 attached to the platen carriage and a dog lever 7 having a pair of dogs which alternately engage the teeth of the ratchet bar and permit a step-by-step 65 movement of the platen carriage under the action of its impelling spring, as well understood in the art.

A universal-bar frame 8 is pivoted about the axis 9 and has a centrally projecting 70 arm 10, the rear end of which is connected by a rod 11 with the horizontal arm or dog lever 7. Attached to an intermediate point of arm 10 is a rod 12 which is connected with the operating mechanism of the ribbon vi- 75 brator.

A key lever 13 is fulcrumed on plate 14 and is resiliently held in normal position by a spring 15. Sub lever 16 is pivotally connected with the key lever and has its lower 80 slotted end working on a fulcrum rod 17 while the upper end thereof has a link connection 18 with a type bar 19.

The construction and operation of the aforementioned parts are well understood by 85 those skilled in the art, and further description thereof is supererogatory.

My invention, as heretofore indicated, comprises a special type bar for indenting papers such as, wills, bank checks, etc., and 90 means for operating this type bar and actuating the letter feed without actuating the ribbon vibrator, for the purpose of producing non-inked indentations in a facile manner. 95

In a typewriter, the ribbon vibrator and letter-feed ratchet are connected with the universal bar and the latter is actuated on depression of each key lever or type bar. In order, therefore, to provide a key lever which is constantly effective to actuate the letter feed and not actuate the ribbon vibrator, it is necessary either (1) to construct the key lever, or type bar, so that it will not actuate the universal bar and then provide an independent connection between the key lever, or type bar, and the letter-feed ratchet, or (2) to have the key lever, or type bar, actuate the universal bar in the usual way and provide means for automatically cutting out 110 the ribbon vibrator on actuation of said key lever. The first mentioned construction is,

perhaps, the simplest in practice, and is the one which I prefer to use.

For carrying out this construction in the particular make of typewriter chosen for illustration, I provide a slot, or notch, 20, in the under side of the particular key lever 13 which controls the check-indenting type bar 19, locating the slot in registry with the universal bar, so that the latter will not be affected by depression of the key lever; and I further provide a one-way connection between said key lever and the letter-feed ratchet. This one-way connection may be conveniently constituted by a rod 21 having its upper end pivoted to the horizontal arm of dog lever 7 and having its lower end engaged in a notch on the under side of the key lever. As shown, the upper end of connecting rod 11 works in a slot in the outer end 20 of the horizontal arm of dog lever 7. In this construction, it is obvious that the normal operation of dog lever 7 by the universal bar is not interfered with by the independent connection 21, while the operation of dog lever 7 by independent connection 21 has no effect on the universal bar and ribbon vibrator. It is apparent, therefore, that key lever 13 is constantly effective to produce non-inked indentations, and that its connections interfere in no way with the operation of the universal bar connections by the other key levers.

Figure 2 illustrates a type block which may be employed for making the indentations. As indicated, this block will make three vertically aligned and substantially round indentations for each actuation of the check-protector key lever. Of course any desired number of indentations, or 40 form thereof, may be employed without departing from my invention.

While, for the purpose of illustration, I have shown my invention applied to a particular make of typewriter, it is clear that 45 the invention may be applied to typewriters of different constructions by modifying the connections shown to suit the particular typewriter, such modifications being within the skill of the mechanic skilled in the type- 50 writer art.

Having thus described my invention what I claim as new and desire to secure by Letters Patent is:

1. The combination with a typewriter 55 having a letter-feed ratchet, a ribbon vibrator, and the usual key levers adapted when actuated to operate both the ratchet and vibrator; of a separate key lever, a type bar operably connected therewith having means for indenting a paper, and means 60 controlled by said separate key lever for actuating the letter-feed ratchet without actuating the ribbon vibrator.

2. The combination with a typewriter 65 having a letter-feed ratchet, a ribbon vi-

brator, and the usual key levers adapted when actuated to operate both the ratchet and vibrator; of a separate key lever and a type bar operably connected therewith having means for indenting a paper, and means 70 operated on depression of said separate key lever for actuating the letter-feed ratchet and not the ribbon vibrator.

3. The combination with a typewriter 75 having a letter-feed ratchet and a ribbon vibrator, and the usual key levers adapted when actuated to operate both the ratchet and vibrator; of a separate key lever and a type bar operably connected therewith having means for indenting a paper, and constantly effective means operated on depression of said separate key lever for actuating the letter-feed ratchet and not the ribbon vibrator.

4. The combination with a typewriter 80 having a letter-feed ratchet, a ribbon vibrator, and the usual key levers adapted when actuated to operate both the ratchet and vibrator; of a separate type bar having means for indenting paper and constantly effective means for operating said 85 separate type bar and letter-feed ratchet only.

5. The combination with a typewriter 90 having key levers, universal bar, letter-feed ratchet and ribbon vibrator, of a type bar having means for indenting a paper, and means for operating said type bar and letter-feed ratchet without actuating the universal bar.

6. The combination with a typewriter 95 having key levers, universal bar, letter-feed ratchet and ribbon vibrator; of a type bar having means for indenting a paper, and means independent of the universal bar for 100 operating said type bar and the letter-feed ratchet.

7. The combination with a typewriter 105 having key levers, universal bar, letter-feed ratchet and ribbon vibrator; of a type bar having means for indenting a paper, a key lever ineffective on the universal bar, and a one-way connection between said key lever and the letter-feed ratchet.

8. The combination with a typewriter 110 having key levers, universal bar, letter-feed ratchet and ribbon vibrator; of a key lever, a type bar connected therewith and having means for indenting a paper, a one-way connection between said key lever and the 115 letter-feed ratchet mechanism actuating said ratchet mechanism on depression of said key lever but permitting said ratchet mechanism to be operated by the universal bar without moving said key lever, said key lever being ineffective on said universal bar.

9. In a typewriter having key levers, universal bar, letter-feed ratchet and ribbon vibrator, a type bar having means for indenting a paper and constantly effective 120

means for operating said type bar and letter-feed ratchet without actuating the ribbon vibrator.

10. In a typewriter having key levers, universal bar, letter-feed ratchet and ribbon vibrator, a type bar having means for indenting a paper, and means for operating

10
said type bar and letter-feed ratchet without actuating the universal bar, said means having a one-way connection with the ratchet.

In testimony whereof I hereunto affix my signature.

LESTER STEWART BARR.
